UNITED STATES PATENT OFFICE

ROY E. CORAM, OF NEWARK, NEW JERSEY, ASSIGNOR TO WESTERN ELECTRIC COMPANY,
INCORPORATED, OF NEW YORK, N. Y., A CORPORATION OF NEW YORK

OSCILLATION GENERATOR

Application filed September 11, 1926. Serial No. 134,777.

This invention relates to the generation of sustained oscillations, and aims to avoid undesired variation of the frequency of the oscillations with temperature.

As an example of applications of the invention, there is shown and described hereinafter in a specific form of electric space discharge oscillator embodying the invention. Temperature changes may cause undesired variation of the oscillation frequency of an electric space discharge oscillator by changing the reactance of a tuning element in the tuned circuit customarily employed for setting the frequency of the oscillator. For example, condensers commonly used for tuning such frequency determining circuits vary in capacity when they are subjected to temperature change. It has been found that, in the range of temperatures at which they are ordinarily operated, their temperature coefficient of capacity is smaller for condensers of large capacity than for condensers of small capacity. Moreover, for reasons indicated hereinafter, as the tuning inductance in the frequency determining circuit of an electric space discharge oscillator is decreased and the tuning capacity in the frequency determining circuit is correspondingly increased to maintain the frequency of oscillation constant, a limiting value of inductance is reached, which is the lowest value that the inductance can have if the system is to generate sustained oscillations of the constant frequency. In accordance with the invention, the tuning inductance is given a value in the neighborhood of this critical value to enable the tuning capacity in the frequency determining circuit to be given approximately its maximum possible value, so that the variation of the frequency of oscillation due to the temperature changes to which the capacity is subjected will be small.

Other objects and features of the invention will be apparent from the following description and claims.

The single figure of the drawing is a circuit diagram of an electric space discharge oscillator embodying a form of the invention.

In the figure is shown an electric space discharge device comprising a vessel 1 enclosing

a cathode 2, an anode 3, and a control electrode or grid 4. Heating current is supplied to the cathode 2 by the source of E. M. F. 5. A source of E. M. F. 6, having its negative terminal connected to the cathode 2 and its positive terminal connected to the anode 3 through a choke coil 7, supplies space current to the discharge device. The control electrode or grid 4 is negatively polarized by a source of steady E. M. F. 8 included in the circuit connecting the cathode and grid of the discharge device, which also includes a coupling coil 9.

The output circuit of the device is provided with two oscillating current paths in addition to the space current path. The first oscillation path extends from the anode 3 through the variable resistance 11, tuned circuit 12 and blocking condenser 10 of large capacity to the cathode 2. The circuit 12 serves to determine the frequency of the oscillations generated. The constants of circuit 12 may be varied by adjusting either the inductance 14 or capacity 15, as indicated by the arrows, or by adjusting both of these elements. The inductance coil included in the tuned circuit 12 is inductively associated with the coil 9. By means of this coupling oscillating current, of a frequency determined by the constants of the circuit 12 and equal to the resonance frequency of that circuit is fed back to the input circuit to control the production of oscillations.

The second oscillating current output path may be traced from the anode 3 through the resistance 13, blocking condenser 10' of large capacity, and load impedance 22, to cathode 2.

The resistance 13 is preferably sufficiently high to prevent changes in the load impedance 22 from unduly affecting the impedance of the oscillating path including it, as seen from the tube 1, and thereby tending to cause undesired change in the frequency of the oscillator.

In order to produce oscillating current of sinusoidal wave form of the frequency determined by the constants of the circuit 12, the resistance 11 should preferably be sufficiently large to limit the amplitude of the

generated waves to such a value that the device 1 operates on the most nearly linear portion of its characteristic curve representing the relation between input voltage and output current. The resistance 11 can also be used to prevent the oscillator from changing its output voltage and consequently the energy delivered to the load 22, due to changes produced in the oscillator frequency by manipulation of capacity 15 or inductance 14. However, the resistance 11 should not be unduly great, since, as will be made apparent hereinafter, the smaller is resistance 11 the smaller may be inductance 14 and the greater may be capacity 15 and, consequently, the smaller will be the changes in the oscillator frequency, caused by temperature variations of capacity 15.

The circuit arrangement as described above is similar to the circuit arrangements disclosed in U. S. patent to Terry, 1,573,948, granted February 23, 1926.

The inductance 14 is preferably of a type in which the temperature coefficient of inductance is small, as for example, an air coretype.

Preferably, condensers which have low temperature coefficients of capacity and at the same time afford considerable magnitudes of capacity in compact and inexpensive form, as for example, the so-called dry stack mica condensers constructed of alternate sheets of metal foil and mica insulation clamped together, are used in obtaining the capacity 15.

Tests have shown the temperature coefficient of the capacity of such condensers to be an inverse function of capacity, in the temperature range in which they are ordinarily employed. Therefore, it is desirable to use condensers having relatively large values of capacity, to give the oscillator stability as regards the frequency of the oscillations generated. For example, according to tests of the temperature coefficient of capacity of commercial dry stack mica condensers, the use of capacity values greater than 0.1 mf., with a maximum temperature coefficient of approximately .0022 per degree Fahrenheit in a temperature range from approximately 50° to 100° F., would result in a maximum variation of about .3 cycle per degree at 30,000 cycles, or a maximum oscillator temperature coefficient of frequency of about .0011% if all other parts of the circuit were perfect. As another example, according to tests of temperature coefficients of commercial dry stack mica condensers, if a condenser having a capacity variable from .01 to .06 mf. furnish nearly all of the capacity in the frequency determining circuit of an oscillator, the oscillator temperature coefficient of frequency will be approximately .0038% or about 1.1 cycles per degree Fahrenheit at 30,000 cycles, again assuming all other parts of the cir-

cuit to be perfect. For a dry stack mica condenser of given capacity, the temperature coefficient of capacity decreases as the area of each plate is decreased, but considerations of economy limit the extent to which it is commercially practicable to reduce the plate area. Moreover, it is in the interest of economy in manufacture to use plates of the same size for condensers of different capacities, as far as practicable.

Although it is desirable to use condensers having as large capacity as possible for tuning the frequency determining circuits of oscillators, there is a limit of capacity which cannot be exceeded in an oscillator employing a given electric space discharge device, because the resonance frequency of the tuned circuit varies as the reciprocal of the square root of the product of the inductance and the capacity of the tuned circuit and, as noted above, as the tuning inductance is decreased and the tuning capacity is correspondingly increased to maintain the frequency of oscillation constant, a limiting value of inductance is reached, below which the system will not oscillate at the given frequency. (When the inductance has any value lower than this critical value, the system will produce no sustained oscillations unless the capacity in the tuned circuit be decreased, in which case the frequency of the oscillations generated will increase.)

It is clear that in the oscillation generating system shown, for continuous operation the voltage impressed on the grid must never be less than 1μ times the voltage developed in the plate circuit. A rigorous calculation of the circuit conditions would include the energy consumed by the resistance R_L of the resistor 13 and the load 22, but in the circuit under consideration this resistance R_L is preferably large compared with the sum of the internal plate to filament resistance of the tube 1 and the resistance R_F of resistor 11, so that, since the omission will greatly simplify the work, the resistance R_L will be considered as infinite in the discussion to follow.

Then, letting

E = voltage generated in plate circuit,
 I = current in resistance 11,
 e = voltage impressed on grid,
 L = inductance of coil 14,
 C = capacity of condenser 15,
 R_F = magnitude of resistance 11,
 R_o = internal plate to filament resistance of tube,
 $\omega = 2 \pi f$ where f is frequency of oscillations generated,
 $Q = \frac{\omega L}{r}$
 r = effective resistance of coil 14 at frequency " f ",

K=voltage transformation ratio of coil 14, the following equations may be written:

$$(1) \quad E = I \left(R_o + R_f + \frac{L}{Cr} \right)$$

(to a close approximation, the accuracy being a function of the value of the impedance of the anti-resonant circuit 12, which at ordinary frequencies closely approximates the last term of the equation) and the limiting value of grid voltage is

$$(2) \quad e = \frac{E}{\mu} = I \frac{L}{Cr} K \text{ or } E = \frac{\mu ILK}{Cr}$$

R_f may be reduced to 0 as a limit so we may write our absolute limiting condition as

$$(3) \quad E = I \left(R_o + \frac{L}{Cr} \right)$$

Equating (2) and (3) and dividing by μ

$$(4) \quad \frac{I}{\mu} \left(R_o + \frac{L}{Cr} \right) = IK \frac{L}{Cr}$$

or (solving for $\frac{L}{Cr}$)

$$(5) \quad \frac{L}{Cr} = \frac{R_o}{\mu K - 1}$$

but

$$(6) \quad C = \frac{1}{\omega^2 L}$$

and

$$(7) \quad r = \frac{\omega L}{Q}$$

substituting in (5)

$$(8) \quad \frac{L}{\omega L} = \frac{R_o}{\mu K - 1}$$

or

$$(9) \quad L = \frac{R_o}{\omega Q(\mu K - 1)}$$

or replacing Q by $\frac{\omega L}{R}$

$$(10) \quad L = \frac{1}{\omega} \sqrt{\frac{R_o r}{(\mu K - 1)}}$$

Equation (9) is an expression for the critical value of L , or the minimum value of L (with an effective resistance of r) that can be used to produce oscillations at the frequency f with a vacuum tube having an amplification constant of μ and a plate to filament impedance of R_o .

The reason why it is impossible to make the ratio of the capacity of the frequency determining circuit to the inductance of that cir-

cuit larger than some critical value and still have the oscillator produce oscillations of a given frequency, is that the effective impedance of the frequency determining circuit is not infinite but is a function of the distributed resistance in the inductance and in the capacity.

The minimum value that the inductance of the frequency determining circuit of an oscillator may have for a given frequency may be determined experimentally, if desired, by decreasing the value of the inductance, while maintaining constant frequency, until the oscillator just ceases to generate sustained oscillations.

In general, the value of resistance 11 is preferably zero when the frequency of the oscillator is approximately at a critical value, that is, when the frequency of the oscillator is approximately at a value below which the oscillator will not generate oscillations unless the inductance of the frequency determining circuit be increased. If the oscillator frequency be then materially increased from that value by decreasing the capacity of the frequency determining circuit, it may be desirable to increase the value of resistance 11 to prevent undue increase in the oscillator output E. M. F. If the desired increase in oscillator frequency be obtained by decreasing the inductance in the frequency determining circuit and also decreasing the capacity in such manner that L will always have the value shown in Equation 9, above, then the value of resistance 11 can ordinarily remain zero through the range of variation of the inductance in which the quantity Q , defined above, remains sensibly constant.

Although the maximum advantage obtainable by use of the invention can be realized in any given oscillator at only one frequency for a given value of inductance in the frequency determining circuit, the applicability of the invention to oscillators and its advantages in that connection are not restricted to single frequency oscillators. When it is desired that an oscillator operate at different frequencies, if the variation of frequency with temperature is to be as small as possible for each frequency then the changes in frequency are preferably obtained by varying the inductance of the frequency determining circuit, so that for each frequency the inductance may have the minimum value consistent with generation of sustained oscillations of that frequency and consequently the capacity of the frequency determining circuit may be correspondingly changed so as to have at each frequency the largest value consistent with the generation of sustained oscillations at that frequency. If it be not feasible to vary the inductance, then the inductance should preferably have the lowest value consistent with the generation of sustained oscillations of the lowest frequency which the oscillator

is required to deliver, the desired frequency changes being then obtained by variation of the capacity of the frequency determining circuit.

In the latter case, it should be borne in mind that for every value of the capacity in the frequency determining circuit, the capacity, or to say the least, that portion of it which changes its value with temperature change should preferably have the largest percentage practicable concentrated in a single condenser. It may frequently be advisable, as for example, for the purpose of adjustment of the total value of capacity in the frequency determining circuit, to employ a relatively small air or mica condenser, or both, in conjunction with a larger (preferably much larger) mica condenser. If, then, the capacity supplied in the circuit by the larger mica condenser be sufficiently large compared to the capacity supplied in the circuit by the smaller mica condenser, the capacity variations of the smaller mica condenser with temperature changes will be such a small percentage of the total capacity in circuit that the smaller mica condenser can not unduly affect the temperature coefficient of frequency of the oscillator even though the capacity of the smaller mica condenser is so low that the temperature coefficient of capacity of that condenser is considerably greater than the temperature coefficient of capacity of the larger mica condenser. Moreover, since the capacity supplied in the circuit by the larger mica condenser will under these conditions be approximately the whole of the capacity in circuit, this condenser will have approximately the same temperature coefficient of capacity that it would have were its capacity equal to the slightly larger value of the total capacity in the circuit. Where the variable capacity in the frequency determining circuit is to afford any desired capacity between, say, 0 and about 0.1 mf., it may, by way of example, consist of one bank of dry stack mica condensers affording a capacity variable from .01 to 0.1 mf., in parallel with an air dielectric condenser variable from zero to about 1200 mmf. and in parallel with a second bank of dry stack mica condensers affording a capacity variable from .001 to .01 mf., the first bank of mica condensers consisting of condensers having capacities of .01, .02, .03, and .06 mf., and the second bank of mica condensers consisting of condensers having capacities of .001, .002, .003 and .006 mf.

In arranging for connection of various combinations of these condensers in circuit, it should be borne in mind that the rate of increase of the temperature coefficient of capacity of dry stack mica condensers with decrease of capacity is greater for small than for large capacity values.

What is claimed is:

1. The method of generating a wave of a

given frequency, utilizing a frequency determining circuit comprising a variable inductance and capacitance in resonant relation, and amplifying means for regeneratively supplying oscillations to said circuit and receiving oscillations therefrom, which consists in setting the inductance at a given value, adjusting the capacitance to the largest value at which oscillations persist, varying the inductance in such direction as to cause the oscillation frequency to more nearly approximate the desired value, readjusting the capacitance as before to the corresponding new limiting frequency, and making repeated readjustments of inductance and capacitance in the above order until the desired oscillation frequency is achieved.

2. The method recited in claim 1, in which the degree of adjustment of inductance and capacitance is made progressively less as the desired frequency is approximated in order to more nearly achieve a final coincidence of desired frequency and maximum capacitance for sustained oscillations.

3. The method recited in claim 1, utilizing in the frequency determining circuit a variable inductance and a variable capacitance element having a capacitance-temperature characteristic which varies inversely as the capacitance.

4. The method of generating a wave of a given frequency, and, for such frequency, having a minimum frequency-temperature coefficient, utilizing a frequency determining circuit comprising a variable inductance and a variable capacitance element having a capacitance-temperature characteristic which varies inversely as the capacitance, and amplifying means for regeneratively supplying oscillations to said circuit and receiving oscillations therefrom, which consists in initially adjusting the resonant frequency of said circuit according to the oscillation frequency desired and subsequently simultaneously decreasing the inductance and increasing the capacitance while keeping the resonant condition, hence the oscillation frequency, constant until a further variation of values tends to prevent the system from sustaining oscillations.

5. The method of generating a wave of a given frequency, and, for such frequency, having a minimum frequency-temperature coefficient, utilizing a frequency determining circuit comprising an inductance coil having an air core and a capacitance element made up of alternate sheets of metal foil and mica insulation, and amplifying means for regeneratively supplying oscillations to said circuit and receiving oscillations therefrom, which consists in initially adjusting the resonant frequency of said circuit according to the oscillation frequency desired and subsequently simultaneously decreasing the inductance and increasing the capacitance while keeping

the resonant condition, hence the oscillation frequency, constant until a further variation of values tends to prevent the system from sustaining oscillations.

5 In witness whereof, I hereunto subscribe my name this 9th day of September, A. D., 1926.

ROY E. CORAM.
